UNITED STATES PATENT OFFICE

138,001

DESIGN FOR A SHEET OF WALLPAPER OR THE LIKE

Thomas M. O'Donnell, New York, N. Y.

Application April 1, 1944, Serial No. 113,112

Term of patent 14 years

(Cl. D59—10)

To all whom it may concern:

Be it known that I, Thomas M. O'Donnell, a citizen of the United States, residing in New York, county and State of New York, have invented a new, original, and ornamental Design for a Sheet of Wallpaper or the like, of which the following is a specification, reference being had to the accompanying drawing, forming a part thereof.

The figure is a top plan view of a sheet of wallpaper illustrating the new design.

I claim:

The ornamental design for a sheet of wallpaper or the like substantially as shown.

THOMAS M. O'DONNELL.
